UNITED STATES PATENT OFFICE

MICHEL BRODSKY, OF PARIS, FRANCE, ASSIGNOR TO WILLIAM WILLHEIM CO., INC.,
OF NEW YORK, N. Y.

DESIGN FOR A TEXTILE FABRIC OR SIMILAR ARTICLE

Application filed November 19, 1932. Serial No. 46,069. Term of patent 3½ years.

To all whom it may concern:

Be it known that I, MICHEL BRODSKY, a citizen of Russia, residing at 132 Bd. Montparnasse, Paris, France, have invented a new, original, and ornamental Design for a Textile Fabric or Similar Article, of which the following is a specification, reference being had to the accompanying drawing, forming a part thereof.

The figure is a plan view of a textile fabric showing the complete width of my new design, except for the portion between the

break lines which is similar to that on either side thereof. The dot and dash lines on the drawing outline substantially the design unit, which unit is repeated in regular succession as indicated by the extensions beyond the unit boundaries.

I claim:

The ornamental design for a textile fabric or similar article as shown and described.

In testimony whereof I have signed this specification.

MICHEL BRODSKY.
